(57) **CLAIM**

The ornamental design for frames for switches, as shown and described.

DESCRIPTION

1. Frame for switches

2. Frame for switches

3. Frame for switches

4. Frame for switches

1.1 : Perspective

1.2 : Front

1.3 : Back

1.4 : Top

1.5 : Bottom

1.6 : Right

1.7 : Left

2.1 : Perspective

2.2 : Front

2.3 : Back

2.4 : Top

2.5 : Bottom

2.6 : Right

2.7 : Left

3.1 : Perspective

3.2 : Front

3.3 : Back

3.4 : Top

3.5 : Bottom

3.6 : Right

3.7 : Left

4.1 : Perspective

4.2 : Front

4.3 : Back

4.4 : Top

4.5 : Bottom

4.6 : Right

4.7 : Left

Reproductions 1.1, 2.1, 3.1, 4.1 are a perspective view; reproductions 1.2, 2.2, 3.2, 4.2 are a front view; reproductions 1.3, 2.3, 3.3, 4.3 are a back view; reproductions 1.4, 2.4, 3.4, 4.4 are a top view; reproductions 1.5, 2.5, 3.5, 4.5 are a bottom view; reproductions 1.6, 2.6, 3.6, 4.6 are a right view; reproduction 1.7, 2.7, 3.7, 4.7 are a left view.
